REFRIGERATOR BODY CONSTRUCTION

Gustave R. Seeger, St. Paul, Minn., assignor to
 Seeger Refrigerator Company, St. Paul, Minn., a
 corporation of Minnesota

Application October 26, 1933, Serial No. 695,335

4 Claims. (Cl. 312—116)

This invention relates to refrigerator body construction and is particularly adaptable to large display refrigerator cases where it is desirable to have a strong durable body construction which 5 may be well insulated so as to retain the refrigerating properties within the same and so as not to be materially affected by the outer atmospheric conditions.

Heretofore refrigerator display cases have been 10 constructed with the body portion made either of wood or angle iron reinforcing frame members which have taken up considerable of the space between the inner and outer walls of the refrigerator body and prevented good and sufficient insulation to be supported between the inner and 15 outer walls of the refrigerator. Where the refrigerator was of a larger display type, this was more outstanding than in the smaller types of refrigerators, and even in the small display refrigerators the wall in the body of the same between the inner and outer surfaces was largely taken up by the reinforcing frame members in wooden beams or angle iron members, riveted, bolted, or otherwise secured together. It will be apparent 20 that with these angle iron members, making up the frames of old types of refrigerators made it difficult to fit cork insulating material or sheets or other insulating material in and about the 25 same without having obvious leaks or filtering of the cold from the inside of the refrigerator to the outside, and heat on the outside material affecting the inside of the refrigerator.

I have overcome these difficulties in a simple 30 yet very practical manner, by forming the body 35 of the refrigerator of comparatively thin sheet members of sheet metal which are formed to give the proper angular shape to the same to form the ends, bottom, top, and front and back of the refrigerator case, and then by welding or 40 otherwise securing these formed sheets together. This provides an exterior body for a refrigerator with a large hollow space between the inner and outer surfaces thereof which may be easily filled with formed sheets or blocks or slabs or loose 45 material cast of insulating material, such as cork, or other suitable insulating material.

With my construction for the body of the refrigerator, I also provide a much larger space 50 for the insulating material, thus providing insulated walls for the refrigerator capable of greater efficiency in collecting and maintaining the desired temperature within the same under various weather conditions.

A further advantage of my refrigerator body 55 construction is that the weight is materially re-

duced without sacrificing any rigidity and in fact, even giving a greater strength and better construction where it is needed. It will be apparent that in large display refrigerator cases, such as are used in stores to display perishable goods, I 5 have accomplished a very desirable means of giving better and more efficient display refrigerator cases in a more economical and efficient manner than has been done heretofore.

It is also a feature of my refrigerator to provide a new method of making the body construction of refrigerators wherein the sheet metal sides 10 form the reinforcing means for the refrigerator body and which may be covered with a flexible insulating material between which the insulating sheets or blocks of pressed cork or other material 15 may be confined and covered by the flexible insulating material, so as to virtually hermetically seal the same together to form a large mass of insulating material in the walls of the 20 refrigerator frame. I have found this construction to be very efficient and much more desirable than the old constructions used heretofore, as hereinbefore set forth, and having the advantages 25 pointed out.

In the drawings forming part of this specification:

Figure 1 is a front view of my refrigerator in the form of a display counter.

Figure 2 is a back view of the same.

Figure 3 is a section on the line 3—3 of Figure 2, in the direction of the arrows.

Figure 4 is a back view of the outer sheet metal shell of my refrigerator.

Figure 5 is a section on the line 5—5 of Figure 4.

Figure 6 is a front view of the outer sheet metal shell.

Figure 7 is an outside end view of the refrigerator, showing the sheet metal end shell.

Figure 8 is a section on the line 8—8 of Figure 6, showing a section through the outside metal shell.

Figure 9 is an enlarged section transversely through my counter display refrigerator, as it would appear when finished with the insulation in the sides of the frame, with the display window in place in the front, with slideable display window doors opposite to the front in the back, and lower compartment doors in the back.

Figure 10 is a diagrammatic perspective detail, showing some of the essential construction of my refrigerator.

My refrigerator A may be made of any suitable design, size or shape, and for convenience I have 55

illustrated a counter display refrigerator in the drawings, which shows a long display form thereof of a type desirable for use in stores for displaying perishable goods therein. The refrigerator A made up in this counter display form is provided with a long front display window 10 which is made up of a series of window panes 11 held together in the frame portions 12 which extend around the window panes and which are designed to hermetically seal the marginal edges of the window panes 11 so that the outer atmosphere will not interfere with the inner atmosphere in the display refrigerator chamber 13. The display window 10 is held in an inclined position extending from the top shelf portion 14 to the front side wall 15 as illustrated in Figure 9.

In the back I provide a series of slideable window doors B which have panes of glass 16 anchored in the frames 17 of the same. The frames 17 slide upon suitable rails 18 which are mounted and formed in the casing of the refrigerator A. These slideable window doors B permit free access to the display compartment so that the merchant can remove or place perishable goods in display on the shelf 19 inside of the chamber 13. Below the display shelf 19 I provide a storage refrigerator compartment 20. Suitable doors C are hingedly supported in the back wall 21 of the casing of the refrigerator A. The bottom wall 22 of the refrigerator A connects the front wall 15 with the back wall 21 and each of the walls 15, 21, and 22 of the refrigerator A are of a thick well insulated construction as will be hereinafter pointed out.

In refrigerators made up as display counters to display perishable goods, usually these refrigerators are of considerable length and heretofore they have had to be made with a very strong inner frame so as to properly support the outer casing in a manner to provide rigidity so that an inner lining could be held therein and the refrigerator could be sturdy and strong so as to be used as a display counter. In these former constructions channel irons have been used to form an inner bracing frame for the refrigerator and also inner wooden frames have been made for this purpose. In either of these old methods, an inner frame of this character is undesirable, primarily because the channel metal iron inner frame is heavy and cannot be made to provide a large enough or unbroken inner compartment for insulating material. In a large display refrigerator it is desirable to provide sufficient insulating material between the inner and outer casings or shell metal portions of the refrigerator to insulate the same sufficiently to give an efficient and practical refrigerating display device. Another objectionable feature of the channel inner iron frames is that the metal inner frame conducts the cold from the inside sheathing or lining to the outside, causing sweating, because, of course, it is necessary to secure the inner and outer shells of the refrigerator to the inner frame. Where a wooden inner frame is used between the shells, a certain conductivity is carried on owing to the continuous and inherent fibres of the wood and, further, the wood frame does not form a practical means of insulation like compressed cork blocks or other similar insulating material which has a higher insulating character. Further, wood frames are more expensive and are heavier and unnecessary as compared with my construction and method of making a refrigerator where it is desirable to have an efficient insulating means at a lower cost.

In my refrigerator the outer covering is a metal shell made up of sheet material such as sheet metal which may be enameled with a vitreous enamel on the outer surface thereof or may have any finish on the same, or may be covered by a separate enameled sheathing. The sheet metal which forms the shell is formed to provide the angular formation of the refrigerator casing so as to form the front wall 15 and the back wall 21, and this sheet metal may be comparatively thin and may be integrally connected together by welding or otherwise, to provide the desired size and shape of the refrigerator shell for the casing. The inner edges of the wall 15 may be turned in with an angular lip 24 formed along the top of the wall 15 and with inwardly turned lips 25 formed around the door opening for the doors C in the back 21 or the display openings, and with an upper turned lip or flange 26 on the upper edge of the back wall 21, all of which form reinforcing means for strengthening and forming rigidity to the shell casing of the refrigerator A. The end portions 27 of the refrigerator are formed of sheet metal and are provided with marginal flanges around the same which extend inwardly and are connected to the sheets which form the front and back walls 15 and 21, respectively. The casing is made up in this sheet metal shell formation with the outer shell portion made up first, as illustrated in Figures 4, 5, 6, 7, and 8, so that the entire outer shell forms a sheet metal construction which includes the bottom portion 22 connecting the front wall 15 with the back wall 21, and with the top shelf portion 14 formed of sheet metal angularly shaped as shown, and connected with the ends and the front window frame and the back window frame. Inwardly turned flanges 28 are formed on the inner edges of the top shelf portion 14, and around each opening in the shell casing similar inwardly extending flanges are formed on the outer sheathing which provides the rigidity around the opening.

The method of constructing the refrigerator is thus carried out by first making up the outer casing in shell formation, as just described, and after this shell is completed, then the inner surface of the sheathing, such as the wall 15, the back 21 and the bottom 22, may be covered with a pliable or flexible insulating material 30 which may be a flexible cement, or asphalt, or other suitable similar material which is sufficiently plastic to be spread on the inner surfaces of the entire sheet metal shell. After the plastic insulating material 30 has been covered over the inner surfaces of the shell, cork blocks of insulating material D are laid against the plastic insulating material 30, being caused to adhere to the same owing to the plastic and sticky nature of the insulating material 30.

This provides a method of permitting large sections of cork blocks D to be laid in place against the inner walls and surface of the shell of the refrigerator A, without any obstructions or inner frame, such as has been used in old forms of refrigerators, and thus my method permits a better construction for a refrigerator where it is obvious that the insulation forms such an important part of the construction thereof.

After the blocks of insulating material which may be of cork or other suitable insulating material, have been laid in place in the shell of the refrigerator, the same may be coated over the outside and between the portions of the blocks, if desirable, with a coat of flexible insulating ma-

terial 31, and then the inner lining 32 is laid in place against the coating 31 or directly against the insulating blocks D. A layer of insulating paper 31' is preferably inserted between the 5 plastic material 31 and the inner lining 32 of the refrigerator so that if the enameled or otherwise finished surface of the lining 32 becomes damaged, this lining may be replaced without the necessity of breaking up the insulating blocks D 10 in the walls of the refrigerator. The lining 32 constitutes the inner lining bottom portion 33, the inner lining front wall 34, the back inner lining wall 35, and the end inner lining wall 36. This inner lining 32 may be enameled or finished 15 in any suitable manner so as to provide the desired inner finishing surface of the refrigerator A. The refrigerator A is preferably made in sections, or halves, as shown, to permit the insertion of the lining 32 into place. The inner lining 20 32 may be secured in any suitable manner to the insulation D which forms the spacing means between the outer shell and the inner lining and at the window display openings an inwardly projecting flange means 37 extends to connect with 25 the inner frame portion 38 as illustrated in Figure 9, as well as an outer flange portion 39 so as to anchor the lining in a suitable manner about the window frame openings. In the back wall 35 an inner flange 40 is formed around the 30 door opening for the doors C. The door openings for each of the doors C is provided with a non-metallic channelled finishing lining 41, which extends to form the door opening with the flanges 25 and 40 and forms a rigid frame structure for 35 the door openings. These channel liner members 41 may be secured in any suitable manner to the shell casing and inner lining.

It is apparent that the insulating material D forms the spacer means between the inner and 40 outer shells of the refrigerator and takes the place of old wood and metal frames, yet provides a rigidity and supporting means sufficient to form a refrigerator of a substantial nature and wherein I have found a means and method 45 of applying the insulation between the shells of the refrigerator to give a greater efficiency than former structures where a frame either of wood or angle iron or other material was used in making up the frame inside of the inner and outer 50 shells of the refrigerator.

My method of making refrigerators simplifies the manufacture and construction and provides a refrigerator cabinet having all of the necessary 55 rigidity and firmness required in the body thereof and yet being of a much lighter weight. This method also permits a refrigerator to be made with a smoother inner and outer finish, requires less bolting and screws for holding the parts together, and permits an inner and outer enameled 60 surface to be employed which may extend over the entire inner and outer surface of the refrigerator cabinet being connected integral. Thus a more sanitary and far more desirable refrigerator 65 may be made, wherein the inner portion is insulated more perfectly from the outside than with older methods and without the possibility of leaks or siphoning from the outside to the inside, or vice versa, because there are no cracks or 70 crevices in the insulation and the inside is insulated virtually perfectly from the outside, even around the display openings and door openings.

It is apparent that the refrigerator A may be built up from the outside shell to the inside shell and completed with the nonmetallic frame members 41 around the door and window openings, or 75

similar nonmetallic frame members. It is also apparent that the refrigerator may be built up by first building the inner casing which comprises the top 32', the bottom 33, the side 34, the side 35, and the ends 36, forming these parts of sheet 5 metal finished as desired with enamel or other suitable material, or with any suitable finish which is adapted to constitute the inside of the refrigerator. Then this inside shell may be covered with the blocks of insulating material D or 10 first covered with a flexible coating of insulating material in the form of a paint or asphalt adhesive material spread over the same, and then applying the blocks D of insulating material. After this, the refrigerator may be finished by applying 15 thin shell-like sheathing which is of metal, finishing by enameling on the outside or otherwise finishing the same by laying sheets of enamel over the same. Before the outside shell has been applied to the insulating material, it is apparent 20 that after the blocks of insulating material are laid in place they may be covered with a second coating of flexible or paint-like insulating material before the outer shell is secured to the same. Then these parts are connected together in any 25 suitable manner to form the body of the refrigerator including the non-metallic or non-conductive framing portions around the door or display openings.

Thus the refrigerator may be built from the outside in or from the inside out, and when it is complete it provides a refrigerator without any inner supporting frame of wood or metal, but just a continuous mass of insulating material which 30 is virtually inherently or integrally connected together, forming a continuous mass of insulating between the shell portions which constitute the inner and outer sheathings. This simplified construction of refrigerator is highly desirable and 35 is an advance in the art of making refrigerators.

The window doors B are mounted upon the 40 rails 18 which are formed in channels of insulating material, like 41, so that there are no metallic parts to cause sweating or siphoning of the cold 45 out of the refrigerator around these openings. The frames of the doors B are of insulating material, such as hard rubber or other suitable non-metallic substance which is not readily affected by heat or cold, while the display window 10 is 50 sealed hermetically between the casings and the insulating material of the refrigerator. A suitable illuminating means E may be associated inside of the shelf portion 14, as illustrated in Figure 9, for illuminating the contents on the display shelf 19 of the refrigerator A.

With this unique, simple, and efficient means of 55 forming the outer shell of the refrigerator cabinet of comparatively thin sheet metal and providing a large free space for thick blocks of insulating material D to be placed between the outer shell and the inner lining, I have accomplished an advancement in the art of making refrigerators 60 which I believe fulfills a long felt want.

Variations may be made within the scope of 65 the following claims and the method may be carried out in the manner set forth or within the equivalent scope to provide a refrigerator of the character set forth.

I claim:

1. The method of making a refrigerator consisting in first forming a two part outer shell of thin sheet metal bent to the desired shape, each part being maintained as a separate unit, then covering the inner surface of each part of the same with an adhesive plastic insulating 70

- material, then laying sheet or blocks of insulating material thereon, then covering the insulating blocks or material with a coating of adhesive plastic insulating material, then applying a two part inner casing which is formed of sheet material over the insulating material, then connecting the parts of each casing together and then placing a heat or cold insulating frame around the display or door openings. 5
2. The method of making a refrigerator consisting in forming a two section outer casing comprising a plurality of parts of thin metal into the desired shape and having display door openings therein, connecting the parts thereof integrally by welding or other suitable means to form a smooth outer surface, then covering the inner surface of each section of said shell-like casing with insulating material, then covering the insulating material of each section with a thin sheet metal lining, then connecting the sections of each casing together, after which the display or door openings are framed with a heat and cold resisting frame portion anchored in place to finish the display or door openings. 10
3. The method of making a refrigerator consisting in forming sheet metal into two sections of the desired shape with window or door openings to act as the shell-like outer casing of the refrigerator, each section being maintained as a separate unit during construction, then covering the outer surface with enamel or the like, then applying insulating means over the entire inner surface of the shell-like casing to the desired thickness and in an integral mass, then covering the insulating material of each section with a thin sheet metal enameled lining and securing the same together, then finishing the door or window openings by framing the same with a non-metallic frame portion and applying the doors or windows thereto. 15
4. The method of making a refrigerator consisting in forming the outer shell in two sections of sheet metal enameled and finished on the outside, each section being maintained during construction as a separate unit, applying insulating material to the desired thickness over the entire inner surface of the shell casing in a manner to virtually become an integral inherent mass, then covering the insulating material of each section with a shell-like sheathing enameled or finished, then connecting with a nonmetallic heat and cold resisting material the inner and the outer shells around the door and frame openings, and connecting the shell-like sheathings to the insulating which holds the same spaced apart to form a refrigerator body with inner and outer shells spaced apart and reinforced by the insulating material. 20 25
